CLAIM

The ornamental design for a candle holder, as shown and described.

DESCRIPTION

FIG. 1 is a candle holder according to the present application.

FIG. 2 is a front view of the candle holder.

FIG. 3 is a side view of the candle holder.

FIG. 4 is a top view of the candle holder; and,

FIG. 5 is a bottom view of the candle holder.

The broken lines in the drawings showing the candle jar illustrate the portions that form no part of the claimed design.
